UNITED STATES PATENT OFFICE.

HANS SCHLAEDEL, OF METZ, GERMANY.

DEVICE FOR LIGHTING GUN-SIGHTS.

SPECIFICATION forming part of Letters Patent No. 731,712, dated June 23, 1903.

Application filed May 8, 1902. Serial No. 106,404. (No model.)

To all whom it may concern:

Be it known that I, HANS SCHLAEDEL, a subject of the German Emperor, residing at 5 Ladouettestrasse, in the city of Metz, Alsace-Lorraine, in the German Empire, have invented a certain new and useful Improvement in Devices for Illuminating Sights of Firearms by Electricity, of which the following is a specification, such as will enable others skilled in the art to which it appertains to make and use the same.

The object of my invention is to provide means for illuminating the front and rear sights of small firearms—such as guns, rifles, and the like—by electricity, so as to make it possible to take the aim with reasonable exactness even in the dark without betraying the position of the shooter. With this point in view the front and rear sights of the gun are each provided with a laterally-arranged incandescent lamp, the circuit of which is so arranged that the shooter in taking the aim can by the operation of a contact by his left hand as it holds the gun close the electric circuit, so as to throw a light simultaneously upon the front and rear sights of the gun while taking the aim. In this operation it is, however, of extreme importance to avoid any dazzling of the eyes of the shooter, and, on the other hand, it is necessary to so arrange the light that the enemy or the animal that is to be shot will not be advised of the position of the shooter or become scared. These difficulties are avoided in my invention, which is especially intended to prevent any dazzling of the eyes of the shooter and the disclosing of the position occupied by the shooter, respectively.

My improved device for lighting the sights of guns is shown in two forms, together with some constructional details, on the accompanying drawings.

Said invention is fully shown and described in the following specification, of which the accompanying drawings form a part, wherein similar letters of reference designate like or equivalent parts wherever found throughout the several views, and in which—

Figure 1 is a side view of a military small-arm rifle provided with my improved sight-illuminating devices. Fig. 2 is a like view of a rifle provided with a circuit of conductors,

including a switch and battery therein from which the illuminating-lamps have been removed, and as such rifle appears when in 55 condition for day-time use. Fig. 3 is a front or face view of my improved form of lamp for illuminating sights. Fig. 4 is a side view of such lamp in central vertical section. Fig. 5 shows in sectional side view and full exterior side view and taken apart the movable lens and light-shielded lamp used by me with adjustable or elevating rear sights, and Fig. 6 is a view of a lamp of somewhat modified form of construction provided with a 65 shield that is removable.

Referring to the drawings, *a* and *b* are clamps or clutches, each of which has a glow-lamp *a'* and *b'*, attached to it laterally and which may be disposed along the barrel of 70 the gun or rifle, so as to throw a strong light upon the sight *c* and the adjustable rear sight *d* from each of the glow-lamps as soon as the circuit is established. Both clasps and the carbons of the glow-lamps are connected by 75 insulated conductor-wires *e* *f* with a battery carried by the shooter, the return-conductor *f* being connected to any suitable switching device of known construction which is attached to a third clamp *g* or which may be attached to 80 the clamp *b* used for lighting the adjustable elevating or rear sight, the press-button of this switch being operated by the shooter when holding the rifle in the position of taking aim by the thumb of his left hand. In 85 this form of construction of my invention, however, the conductor-wires are liable to interfere with the handling of the rifle or they may be injured when the rifle is carried through the woods or by similar obstacles on 90 the way. These inconveniences are avoided in the form of construction shown in Fig. 2 of the drawings. In this modification the conductor-wires *e* *f* are embedded in the wooden casing of the gun-barrel and the dry battery 95 used as a current-generator is interchangeably mounted in the butt-end of the rifle or gun. The switch is included in the return-conductor *f* in such a manner that its press-button *h* is just in the place where the rifle 100 when in position for firing is grasped by the hand, so as to effect a closing of the circuit while taking aim and to cause the illumination of the sights. The glow-lamps may be

provided with clamps the same as in the construction shown in Fig. 1 of the drawings, these clamps being placed upon the barrel and constituting the electric connection with the carbons of the glow-lamps. The latter arrangement is not made use of in the modification shown in Fig. 2, but small holes *k* in the wooden casing are used instead, which serve for the reception of the well-known plug-contacts and which, being in electric connection with the glow-lamps, will when introduced in these holes include the glow-lamps in the circuit.

While by providing a rifle or gun with the device for lighting the sights in the manner specified the exactness of taking aim even in the dark is so greatly increased on account of the press-button for establishing the contact being arranged just where the gun or rifle is supported by the hand of the shooter, who is thus enabled to actuate the lighting device without the necessity of any manipulation interfering with steady aiming, still the efficiency of the rifle, and in particular when used before the enemy, is impaired by the dazzling of the eye of the shooter by the glaring though small light of the glow-lamps and by the possibility of betraying the position of the shooter in this manner; yet it is necessary to throw as intense a light as possible upon the sight and the adjustable rear sight, inasmuch as otherwise the outlines of these parts do not present themselves with sufficient exactness which in turn would result in exact aiming.

The inconvenience referred to is avoided in my invention by inclosing the glow-lamps by a casing *i*, of opaque or light-subduing material, which surrounds the glow-lamp on all sides, Fig. 3, but for an opening *l*, directed toward the adjacent sight, so as to allow the rays projected through this opening to strongly light such sight. When so arranged, the light is prevented from dazzling the eyes of the shooter and can be seen by the enemy only at extremely close range. As a result I may use glow-lamps of very strong illuminating power, or in the case of weaker lamps I may concentrate the light by arranging a lens *m*, Fig. 4, in the opening of the casing *i*, so as to throw a light of sufficient intensity upon the adjacent sight. In lighting the adjustable elevating or rear sight, however, it becomes necessary to change the direction of the rays of light with the adjustment and the change of position of the sight. In view of this the lighting device for this sight is also made adjustable. In the preferred form of construction shown in Fig. 5 of the drawings the casing or hood *i* of the glow-lamp is made adjustable, inasmuch as it is capable of rotating in a horizontal and vertical direction with relation to the lamp. For this purpose the fitting of the glow-lamp is tightly covered by a dish-shaped bottom part *i'*, and on this is fitted the upper part of the covering, which constitutes the casing *i* proper and which is provided with spring-acting projections, so as

to enable it to be fitted over the dish-like bottom part *i'*. By this means the cone of light may be adjusted with great facility and exactly corresponding to the position of the sight. To the rotatable upper part *i* an arm *n* is attached, as shown in Fig. 5 of the drawings, which extends across the stationary portion of the rear sight and into the path of the adjustable portion or sight-leaf, such adjustable portion or sight-leaf on being raised striking against the said arm *n*, which is moved thereby, giving a rotation in a vertical direction to the casing or hood *i* in consequence. By this means when the lens *m* or the opening in the casing has been properly arranged I am able to automatically direct the light exactly upon the sight-notch of the rear sight at whatever height the same may be situated. There is no necessity of such adjustment for the front sight, and in this case the more simple construction shown in Figs. 3 and 4 is sufficient.

In order to facilitate the mounting of the hood or casing *i* upon the glow-lamp *b* and in order to avoid the necessity of renewing the casing or hood on replacing a worn-out lamp, it is preferable to make the casing in two sections, as shown in Fig. 6 of the drawings. In this modification the casing *i* is vertically divided, the parts being connected to each other by the curved spring *o*, the said spring pressing the two sections against each other and securing them in position upon the lamp, while an upward pull will be sufficient to remove the casing from the lamp, the spring *o* acting as a handle.

What I claim, and desire to secure by Letters Patent of the United States, is—

1. An electric glow-lamp for use in illuminating firearm-sights provided with an opaque movable covering carrying a lens for transmitting the light, substantially as shown and described.

2. The combination with a firearm, of a circuit of conductors having included therein a battery and a switch, a front sight, and a glow-lamp also included in the circuit located adjacent to the front sight adapted to cast a beam of light upon the front sight when the circuit is closed without illumination in any other direction, an adjustable or elevating rear sight, a glow-lamp adjacent to the rear sight also included in the circuit, an opaque hood covering the lamp and adjustable thereon, and a lens carried by the hood for directing a beam of light upon the rear sight, substantially as shown and described.

3. The combination with a firearm, of a circuit of conductors having included therein a battery and a switch, a front sight, a glow-lamp also included in the circuit located adjacent to the front sight adapted to cast a beam of light upon the front sight when the circuit is closed without illumination in any other direction, an adjustable or elevating rear sight, a glow-lamp adjacent to the rear sight also included in the circuit, an opaque

hood covering the lamp and adjustable thereon having a small light-emitting orifice or means, and means for moving the hood in actuating connection with the moving portion 5 of the rear sight whereby the two will be moved in unison and the beam of light be directed upon the sight at all times, substantially as shown and described.

4. The combination with a firearm, of a circuit of conductors having included therein a battery and a switch, a front sight, a glow-lamp also included in the circuit located adjacent to the front sight adapted to cast a beam of light upon the front sight when the circuit is closed without illumination in any other direction, an adjustable or elevating rear sight, a glow-lamp adjacent to the rear sight also included in the circuit, an opaque hood covering the lamp and adjustable thereon, a lens carried by the hood for directing a beam of light upon the rear sight, and means 20 for moving the hood in actuating connection with the moving portion of the rear sight

whereby the beam of light will fall upon the sight in all positions thereof, substantially as 25 shown and described.

5. The combination with a firearm, of a circuit of conductors having included therein a battery and a switch, a front sight, a glow-lamp also included in the circuit located adjacent to the front sight adapted to cast a beam of light upon the front sight when the circuit is closed, an adjustable or elevating rear sight, a glow-lamp adjacent to the rear sight also included in the circuit, an opaque 30 movable hood inclosing the rear-sight lamp, and a light-transmitting lens carried by the movable hood for directing a beam of light upon the rear sight, substantially as shown and described.

In witness whereof I have hereunto set my hand in presence of two witnesses.

HANS SCHLAEDEL.
